UNITED STATES PATENT OFFICE

2,638,380

MECHANICAL LIFTING MECHANISM FOR
DUMP TRUCKS

Robert C. Best, Indianapolis, Ind.

Application April 7, 1950, Serial No. 154,600

6 Claims. (Cl. 298—21)

1

The present invention relates to a mechanical lifting mechanism for dump trucks and it consists in the combinations, constructions and arrangements of parts herein described and claimed.

Generally there is provided a mechanical lift for dump trucks wherein there is provided a chassis to which is pivotally connected at one end a bed frame of the body. Pivotally connected to the chassis is an elongated cylinder reciprocable therein which piston is provided with a rod which extends through the free end of the cylinder to connect with novel links and leverage which are, in turn, connected with the body frame. A cable is entrained over pulleys carried by the piston and cylinder and one end of the cable is affixed to the chassis while the other end is entrained over a drum which is motivated by means of a winch which is, in turn, moved by a shaft connected with a source of power. The shaft is provided with a brake which may be controlled by the operator.

It is accordingly an object of the invention to provide an apparatus of the character set forth which is simple in construction, comparatively inexpensive to manufacture, and yet effective and efficient in use.

Another object of the invention is the provision of novel means for transmitting motion between a source of power associated with a chassis and a dump truck body frame pivotally connected to such chassis.

Another object of the invention is the provision of novel means for guiding a rod utilized in the invention.

A still further object of the invention is the provision of a novel arrangement of links and levers forming a part of the invention.

Other and further objects of the invention will become apparent from a reading of the following specification taken in conjunction with the drawings, in which:

Figure 1 is a plan view of an embodiment of the invention,

Figure 2 is a side elevational view of Figure 1,

Figure 3 is a sectional view taken substantially along line 3—3 of Figure 1,

Figure 4 is a view similar to Figure 3 but showing certain parts of the invention advanced to other positions,

Figure 5 is an enlarged fragmentary horizontal sectional view illustrating certain details of construction,

Figure 6 is a sectional view taken along line 6—6 of Figure 5, and

2

Figure 7 is a fragmentary perspective view illustrating certain links and levers utilized in the invention.

Referring more particularly to the drawings, there is shown therein a chassis having side pieces 10, end pieces 11 and provided with axles 12 and supporting wheels 13, the chassis being rectangular in shape.

A body supporting frame is provided and consists of a pair of elongated side members 14 interconnected by end members 15 at either end thereof. Each of the side members 14 is formed with a dependent ear 16 adjacent the rear end thereof and each of the ears 16 is pivotally connected by means of a pin 17 to one of the respective sides 10 of the chassis.

The chassis is provided with a pair of spaced cross bars 18 and 19 adjacent the forward end thereof and a rearwardly extending cylinder 20 is hinged centrally to the cross bar 18, as indicated at 21. The rearward or free end of the cylinder 20, indicated at 22, is provided with a journal 23 in which is slidably mounted a piston rod 24 the forward end of which has formed thereon a piston 25 which is slidable within the cylinder 20.

The rearward end of the rod 24 has affixed thereto a laterally extending web 26 the rearward end of which is welded or otherwise affixed to a transversely extending cylindrical member 27 which is, in turn, revolvably mounted upon a shaft 28 which is affixed at either end to the upper corner of a triangular plate 29 each of whose lower rearward corners is pivotally mounted upon a transversely extending shaft 30 affixed to the sides of the chassis.

A link 31 interconnects the forward lower corner of the plate 29, as indicated at 32, with the adjacent side 14 of the frame, as indicated at 33.

A cable 34 is anchored at one of its ends to the cross bar 18 of the chassis, as indicated at 35, and extends thence rearwardly to a sheave 36 mounted upon a shaft 37 which extends vertically across an opening 38 found in one side of the rear wall 22 of the cylinder 20. The cable 34 then extends forwardly through an opening 39 in the piston 25 to a pulley 40 carried upon the forward side of the piston and thence through an opening 41 in the piston to a pulley 42 carried centrally on the forward side of the rear wall 22 of the cylinder 20. It thence extends rearwardly through an opening 43 over a pulley 44 carried on the forward side of the piston 25 and thence rearwardly through an opening 45 in

the piston 25 to and over a pulley 46 mounted upon a shaft 47 which extends vertically across an opening 48 in the rear wall 22 of the cylinder 20. The cable 34 then extends forwardly through an opening 49 in the cross bar 18 to a drum 50.

The drum 50 is affixed to a shaft 51 which extends through a pair of bracket arms 52 carried by the cross bar 18 and thence through a gear housing 53 whose base 54 inter-connects the cross bars 18 and 19.

The shaft 51 has affixed thereto within the housing 53 a bevel gear 55 which is enmeshed with a bevel gear 56 likewise mounted within the housing 53 and carried at the rearward end of the shaft 57 which is, in turn, connected by a coupling 58 with a suitable source of power. The shaft 57 carries a brake drum 59 with which is associated a brake band 60 operable from a remote point by means of a control rod 61. A bracket 62 supports the brake mechanism.

In operation, it will be apparent that normally the body supporting frame will lie in a horizontal position, as indicated, for example, in Figure 3 of the drawings. When, however, it is desired to tilt the frame and its accompanying body (not shown), it is only necessary to supply power, through the connection 53 to the shaft 57 to thereby turn the same, which action will, through the gears 56 and 55, act to revolve the shaft 51 and consequently the drum 50 to thus wind the cable 34 upon such drum.

Since the cable 34 is anchored to the cross bar 18 at 35, such action will cause the piston 25 and consequently the rod 24 to be drawn in a rearward direction thus, through the agency of the web 26 and its tubular connection 27 with the shaft 28 causing the plates 29 to revolve in a counterclockwise direction upon the shaft 30 as viewed, for example, in Figures 3 and 4. As a result of this action the forward end of the plates 29 will be caused to rise thus, through the associated links 31 causing the frame likewise to be lifted and revolved upon its pivotal connections 17, also as viewed for example, in Figures 3 and 4.

It will be seen that that portion of the cable 34 which is affixed at 35 will act to balance the strain put upon the piston 25 by the remainder of the cable 34 when the same is wound upon the drum 50. It will also be seen that the piston 25, the journal 23, and the pulleys 40, 42, and 44 will act together to maintain the rod 24 in constant parallel relation with the walls of the cylinder 20.

When the body supporting frame has been lifted to a desired height, the operator of the apparatus may, through the use of the conventional control rod 61 cause the brake bands 60 to contract upon the brake drum 59 to thereby stop any further motion. It will also be apparent that when it is desired to return the body supporting frame to its original position, that it is only necessary to cease any application of power to the shaft 57 and to then allow the same to be lowered by gravity, the brake 59—60 being utilized to control such downward movement of the frame to thereby avoid any breakage of the various parts of the apparatus which might otherwise occur.

While but one form of the invention has been shown and described herein, it will be readily apparent to those skilled in the art that many minor modifications may be made herein without departing from the spirit of the invention or the scope of the appended claims.

What is claimed is:

1. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slidable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, and a source of power for turning said winch whereby, when said cable is wound thereon, an outward thrust is given said piston and said piston rod.
2. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slidable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, and a source of power for turning said winch whereby, when said cable is wound thereon, an outward thrust is given said piston and said piston rod.
3. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slidable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, and a source of power for turning said winch whereby, when said cable is wound thereon, an outward thrust is given said piston and said piston rod, a shaft connecting said winch with said source of power, and a brake for said shaft.
4. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slidable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, and a source of power for turning said winch whereby, when said cable is wound thereon, an outward thrust is given said piston and said piston rod, said linkage and levers comprising a pair of vertically extending triangular plates each having its rearward lower corner pivoted to one side of said chassis, a link interconnecting the forward lower corner of said plate with one side of said frame, a transverse shaft interconnecting the upper corner of each plate, a tubular member revoluble upon said

shaft and a web centrally affixed to said tubular member and to said rod.

4. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slideable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, a source of power for turning said winch whereby, when said cable is wound thereon, an outward thrust is given said piston and said piston rod, and a shaft interconnecting said winch with said source of power, and a brake for said shaft, said linkage and levers comprising a pair of vertically extending triangular plates each having its rearward lower corner pivoted to one side of said chassis, a link interconnecting the forward lower corner of said plate with one side of said frame, a transverse shaft interconnecting the upper corners of said plates, a tubular member revolute upon said transverse shaft, and a web centrally affixed to said tubular member and to said rod.

5. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slideable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, and a source of power for turning said winch whereby, when said cable is wound thereon, an outward thrust is given said piston and said piston rod, said linkage and levers comprising a pair of vertically extending triangular plates each having its rearward lower corner pivoted to one side of said chassis, a link interconnecting the forward lower corner of said plate with one side of said frame, a transverse shaft interconnecting the upper corners of the plates, a tubular member revolute upon said transverse shaft, and a web centrally affixed to said tubular member and to said rod, said web being formed in the shape of an isosceles triangle having its base formed integrally with said tubular member and its apex portion affixed to said rod.

forward lower corner of said plate with one side of said frame, a transverse shaft interconnecting the upper corner of each plate, a tubular member revolute upon said transverse shaft, and a web centrally affixed to said tubular member and said rod, and said web being in the form of an isosceles triangle and having its base formed integrally with said tubular member and its apex portion affixed to said tube.

6. An apparatus of the character described comprising a chassis of rectangular construction, a body-supporting frame likewise of rectangular construction pivotally connected at its rear end to the rear of said chassis, a cylinder centrally hinged to said chassis for vertical movement, a piston rod extending rearwardly through the free end of the cylinder, a piston affixed to the inner end of the rod and slideable within the cylinder, a sheave mounted at either side of the free end of the cylinder, a sheave mounted at either side of the forward face of the piston, a sheave centrally mounted upon the inner face of the free end wall of the cylinder, a winch mounted upon said chassis, a cable anchored to said chassis at one end, entrained over said sheaves and connected to said winch at its other end, linkage and levers connecting the outer end of the rod, said chassis and said frame, a source of power for turning said winch whereby, when said cable is wound thereon, an outward thrust is given said piston and said piston rod, a shaft interconnecting said winch with said source of power, and a brake for said shaft, said linkage and levers comprising a pair of vertically extending triangular plates each having its rearward lower corner pivoted to one side of said chassis, a link interconnecting the forward lower corner of said plate with one side of said frame, a transverse shaft interconnecting the upper corners of the plates, a tubular member revolute upon said transverse shaft, and a web centrally affixed to said tubular member and to said rod, said web being formed in the shape of an isosceles triangle having its base formed integrally with said tubular member and its apex portion affixed to said rod.

ROBERT C. BEST.
